(57) **CLAIM**

The ornamental design for grooving insert for machine tools, as shown and described.

DESCRIPTION

1.1 is a perspective view of grooving insert for machine tools showing my new design;

1.2 is a front view thereof;

1.3 is a back view thereof;

1.4 is a top view thereof;

1.5 is a bottom view thereof;

1.6 is a left view thereof; and

1.7 is a right view thereof.

The broken lines in the figures depict portions of the grooving insert which form no part of the claimed design.
